SLICE DEFLECTOR FOR SLICING MACHINES

Filed Sept. 16, 1927

Inventor:
Henry Thomas
By Vise and Done

Attest.

UNITED STATES PATENT OFFICE.

HENRY THOMAS, OF EAST HAM, LONDON, ENGLAND, ASSIGNOR TO U. S. SLICING MACHINE COMPANY, OF LA PORTE, INDIANA, A CORPORATION OF INDIANA.

SLICE DEFLECTOR FOR SLICING MACHINES.

Application filed September 16, 1927. Serial No. 219,829.

This invention relates to deflectors for directing slices away from the rotary knives of slicing machines, and has for one of its objects the provision of a support for deflectors of this nature which will hold the deflector in position adjacent the face of the slicing knife so that the deflector will not be moved out of position by the slices engaging the edge of the deflector.

10 A further object is to provide a deflector which is locked in operative position and in which the force of the slices, as they are being cut, tends to hold the deflector in its locked position.

15 A further object is to provide a deflector which will overlap its support when in operative position to prevent any gap or open space between the deflector and support.

20 A further object is to provide an adjustable support for the deflector which will permit the edge of the deflector to be adjusted relative to the face of the slicing knife.

25 Other objects and advantages will appear from the following description.

The invention is exemplified in the combination and arrangement of parts shown in the accompanying drawing and described in the following specification, and it is more particularly pointed out in the appended claims.

In the drawing—

Fig. 1 is an elevation of a portion of a slicing machine knife showing one embodiment of the present invention applied thereto;

Fig. 2 is a top plan view of the deflector shown in Fig. 1;

Fig. 3 is a section on line 3—3 of Fig. 1; and

Fig. 4 is a view similar to Fig. 3, but showing the parts in a different position.

This invention is somewhat similar to the device shown in my prior application, Serial No. 141,434, filed October 14, 1926, but shows a different form of pivotal support for the deflector.

The numeral 10 designates the bearing support for a slicing machine knife 11 which is journaled at 12 on the support 10. A plate 13 is secured to the side of the support 10 by screws 14 and is provided with laterally projecting brackets 15 having bearing openings 16 therein. The brackets 15 are pro-

vided with slots 17 which communicate with the inner sides of the openings 16. The deflector plate 18 is provided with inwardly projecting ears 19 and 20. The ear 19 carries a downwardly projecting lug 21 of a size and shape to fit into the opening 17 in the lower bracket 15. The ear 20 carries an upwardly projecting lug 22 shaped to fit within the opening 17 of the upper bracket 15. Spring rings 23 disposed in the openings 16 in the brackets 15 retain the lugs 21 and 22 in position in the slots 17. The rings 23 are open at one side and the lugs 21 and 22 are provided with rounded edges which engage the openings in the rings. So long as the lugs 21 and 22 are positioned in the slots 17, the deflector 18 will be held in place against the face of the knife 11. When it is desired to swing the deflector outwardly away from the knife, this may be done by pressing the deflector to the right, as viewed in the drawing, to move the lugs 21 and 22 through the openings in the rings 23 until they occupy a position within the interior of the rings 23, as shown in Fig. 4. The deflector 18 may then be swung outwardly, as indicated in Fig. 4, the rings 23 rotating in the openings 16 to provide a pivotal support for the deflector 18. The deflector 18 is provided with an opening 24 to permit the insertion of the operator's thumb or fingers to shift the deflector for moving the lugs 21 and 22 into and out of engagement with the slots 17. A reinforcing bracket 25 surrounds the opening 24 and braces the ears 19 and 20 which support the lugs 21 and 22.

In the operative position of the deflector, the lugs 21 and 22 are engaged in the slots 17 and the rounded ends of the lugs register with the gaps in the rings 23 and the deflector is thus locked against turning movement. When the deflector is shifted toward the edge of the knife to release the lugs from the slots 17, the rings 23 will be sprung outwardly into frictional contact with the inner faces of the openings 16 and thus serve to maintain the deflector in any position into which it may be swung. Co-operating stops 26 and 27 on the deflector 18 and the supporting brackets 15, respectively, are provided for guarding against accidental movement of the deflector into contact with the face of the knife. When the deflector is

shifted to the right as viewed in the drawing out of its operative position, the stops 26 on the deflector move into a position which registers with the stops 27, the deflector being thus prevented from swinging further toward the knife than the amount determined by the stops 27. Cover plates 28 are fitted on the outer surfaces of the brackets 15 to close the openings 16 and prevent ingress 10 of grit to the rings 23. The upper cover plate is removed in Fig. 2 for the purpose of clearance. Openings 29 are cut in the walls of the brackets 15 to permit the lugs 21 and 22 to pass when fitting the deflector into 15 position in the supporting brackets or when removing the deflector from its brackets. The plate 13 is attached to the knife bracket 10 by screws 14, as previously explained, the screws being arranged to permit the plate to 20 move through a slight angle and a grub screw 30 is provided to hold the plate 13 in its adjusted positions. By this means the inclination of the deflector to the knife can be adjusted at will. It should be noted that 25 when the deflector is in its operative position the pivotal point thereof is moved back toward the support 10 to such a position that the rear edge of the deflector overlaps the supporting member so that no joint is visible 30 between the deflector and support.

I claim:—

1. In a slicing machine, a guard plate for the slicing knife, a support for said guard plate comprising pivot members movable 35 transversely of the axis thereof, and means co-operating with said pivot members for holding said members against pivotal movement when said guard plate is in its operative position, said pivot members being 40 movable to a position in which they are free to rotate about their axis to permit said guard plate to swing away from the slicing knife.

2. In a slicing machine, a guard plate for 45 the slicing knife, and a support for said guard plate comprising a bracket having an opening therein provided with a circular and a non-circular portion and a pintle on said guard plate disposed in said opening and 50 shiftable with said guard plate from one portion of said opening to the other.

3. In a slicing machine, a slice deflector, and a support for said deflector comprising 55 a member having a slotted opening therein and a pin mounted in said opening and movable transversely therein, said pin being locked against rotation in one position in said opening and free to rotate in another position to permit said deflector to swing to 60 an inoperative position.

4. In a slicing machine, a slice deflector having a pin provided with a flattened face and a bracket for receiving said pin, said bracket having an opening provided with a 65 circular portion and a non-circular portion,

and means for retaining said pin in said non-circular portion to prevent rotation of said pin when said slice deflector is in its operative position.

5. In a slicing machine, a slice deflector, 70 and a support for said deflector comprising a bracket having an opening therein and a pin mounted in said opening, said opening having a circular portion and a non-circular portion, said deflector being movable in the 75 direction of the plane thereof to shift said pin from one portion of said opening to the other, and yielding means for retaining said pin in said non-circular portion to hold said deflector against pivotal movement when 80 said deflector is in its operative position.

6. In a slicing machine, a slice deflector, a support for said deflector arranged to permit movement of said deflector in the direction of the plane thereof and to lock said 85 deflector against pivotal movement when in one position but to permit pivotal movement when in a different position, and means for adjusting said support to change the angular position of said deflector when said deflector is locked.

7. In a slicing machine, a slice deflector, a pin having a flat face thereon mounted on said deflector, a bracket member having an opening therein provided with a circular portion and a communicating slot, said pin being disposed in said opening and shiftable 95 therein from one portion to the other, and a spring clip disposed in the circular portion of said opening for yieldingly retaining said pin in the non-circular portion of said opening and for providing frictional resistance to pivotal movement of said deflector when said pin is moved into the circular portion of said opening. 100

8. In a slicing machine, a slice deflector, a pivotal support for said deflector arranged to permit movement of said deflector transverse to the pivotal axis of said support, means for locking said deflector against pivotal movement when in one position, and means for limiting the pivotal movement of said deflector when said deflector is in a different position. 110

9. In a slicing machine, a slicing knife, a 115 deflector for directing slices away from said knife, a pivotal support for said deflector arranged to permit movement of said deflector transverse to the axis of said support, means for locking said deflector against pivotal movement when in one position, and means for limiting the pivotal movement of said deflector toward said knife when said deflector is in a different position. 120

10. In a slicing machine, a slicing knife, a 125 deflector for directing slices away from said knife, a supporting bracket for said deflector having a circular opening therein provided with a slotted extension, a flattened pin for supporting said deflector arranged in said 130

- opening and movable into and out of said slotted extension, said pin and extension being shaped to hold said deflector against pivotal movement when said deflector is in its operative position relative to said knife, and a stop for limiting the movement of said deflector toward said knife when said pin is shifted into said circular opening to permit pivotal movement of said deflector.
11. In a slicing machine, a slice deflector, a supporting bracket for said deflector having a circular opening therein provided with a slotted extension, a supporting pin mounted in said opening and having a flattened face for co-operating with said slotted extension to hold said deflector against pivotal movement, a circular spring clip disposed in said opening and having a slot in the side thereof for engaging said pin to hold said pin in said slotted extension but permitting movement of said pin into the interior of said clip to permit pivotal movement of said deflector, a stop for limiting the pivotal movement of said deflector, and means for adjusting the position of said bracket to vary the angular position of said deflector when said pin is disposed in said slotted extension.
12. In a slicing machine, a slicing knife, a support for said knife, a plate mounted on said support, means for adjusting the position of said plate on said support, a pair of spaced brackets carried by said plate, each bracket having a circular opening therein provided with a slotted extension, and a gap in the side of said opening, split spring rings mounted in said circular openings, a slice deflector, flattened pins carried by said deflector shaped to fit the slotted extensions of said openings, said deflector being movable in the direction of the plane thereof to shift said pins from said slotted extension into the interior of said split rings in which position said pins permit rotation of said deflector toward and from the slicing knife, and stops for limiting the pivotal movement of said deflector toward the slicing knife.

In testimony whereof I have signed my name to this specification on this 26th day 50 of August A. D. 1927.

HENRY THOMAS.
